SELF-LATCHING MILK BOTTLE BOX

Arthur L. Willett, Denver, Colo.

Application April 25, 1938, Serial No. 204,030

3 Claims. (Cl. 232—41)

This invention relates to improvements in milk bottle boxes or casings and has reference more particularly to a self latching milk bottle box.

Milk is almost universally delivered to customers in glass bottles and since the deliveries usually take place at night or in the early morning, it sometimes happens that milk thus left handily available is stolen. In cold weather the milk also freezes if left exposed too long.

10 It is the object of this invention to produce a two compartment self latching box, one compartment of which is provided with a cover and which is so constructed that when the milk is delivered it is placed in the covered compartment and the cover closed. A spring latch holds the cover in closed position until it is opened by a suitable means. The box can be made of any suitable material, but is usually made from wood or from a fibrous press board of the type known 15 as Celotex. When the box is made from a material of poor heat conducting material, it serves to retard freezing in cold weather.

In order to describe this invention so that it can be readily understood, reference will be had 20 to the accompanying drawing in which the preferred embodiment has been illustrated and in which:

Figure 1 is a perspective view showing the box with the cover closed;

30 Figure 2 is a horizontal section taken on line 2—2 Fig. 1 and shows the parts in locked position;

Figure 3 is a section taken on line 3—3 Fig. 1 and shows the parts with the cover unlocked.

35 Figure 4 is a section similar to Fig. 3 but shows the cover locked; and

Figure 5 is a section taken on line 5—5 Fig. 4.

The box is of usual construction and has a bottom 5, two sides 6, two ends 7, a cover 8 and 40 a partition 9. In the drawing the box has been shown of considerably greater length than width and of a height slightly greater than that of a quart milk bottle. The interior of the box is divided into two compartments A and B by the 45 partition 9 which is secured between the sides 6 so as to rock about a pivot 10. Compartment B is of a size to receive a quart milk bottle with a small clearance.

At the lower end of compartment B is a false bottom 11 which is elevated above the upper surface of bottom 5 so as to leave space for a helical tension spring 12 whose ends are anchored to the end wall 6 and to the lower end of partition 45.

50 Spring 12 is quite powerful and is under quite high tension when the parts are in the position

shown in Fig. 2, so that a considerable force is required to tilt the partition from that position to the one shown in Fig. 3.

The cover is attached to one end wall 7 by means of hinges 13 that are of a peculiar construction and which each consists of a metal plate whose lower end is inserted in a slot cut in the upper end of wall 7 and whose upper end is positioned in a similar slot in the corresponding end of the cover. Two pins secure the hinge plates 10 to the box end and a single pin 14 secures the cover to the upper ends of the hinge plate. Secured to the under side of the cover near its movable end, is a nose plate 15 having a hole for the reception of the pin 16 on the partition. When 15 pin 16 is in the hole in plate 15 the cover is locked in closed position and cannot be opened until the partition 9 is rocked about its pivot to the position shown in Fig. 3.

It will be observed that a cam surface is 20 formed on the outside of the partition by a strap 17 whose ends are attached to the partition by screws, as shown.

Let us now assume that the customer has an empty quart milk bottle and expects the milk 25 man to deliver another in the morning. He inserts the empty bottle in compartment B and when this engages the cam surface of strap 17 it rocks the partition to the position shown in Fig. 3, in which position cover 8 is unlocked. 30 The milk man opens the cover, puts a milk bottle into compartment A, closes the cover and removes the empty bottle from chamber B. Pin 16 projects through the opening in plate 15 and locks the cover.

When the customer wants to remove the milk, a quart bottle is inserted in chamber B and this serves as a key to unlock the cover.

If the cover is locked when the milkman comes to deliver, he merely uses one of his own bottles 40 to unlock the cover.

It will be seen from the above that this safety box is of very simple construction and is quite reliable in its action. To a person not acquainted with its construction it is very difficult to open 45 as spring 12 is made so powerful that it is difficult for even a strong person to rock the partition. Owing to the wedge action between the bottle and the cam surface, the partition can be rocked against a very strong force.

The hinge is so constructed that it will stand up under rough usage and is both strong and cheap to construct.

It is, of course, possible to substitute for the helical spring another equivalent spring and to 55

substitute for the cam 17 some specifically different cam surface. It is also evident that the position of the pivot 10 can be raised or lowered to secure the best results. The latch shown is 5 merely illustrative of means for this purpose and specifically different latching means can be substituted.

Having described the invention what is claimed as new is

- 10 1. A self locking milk box comprising in combination, an open box having parallel sides, a partition positioned between the sides, nearer one end than the other, whereby the box is divided into two compartments of unequal size, a cover hinged to one end wall of the larger compartment, a movable edge of the cover terminating adjacent the wall of the partition facing the smaller compartment, the smaller compartment being open, a pivot operatively connected with 15 the partition which is rockable about the pivot, means comprising a spring, forming a resilient connection between the partition and the box, the spring tending to move the lower end of the partition into the smaller compartment, means 20 comprising stops carried by the box for limiting the rocking of the partition by the spring, a perforated nose piece secured to the under side of the cover adjacent the partition, a pin on the 25 partition positioned to enter the hole in the nose piece when the cover is closed, and an inwardly 30 and downwardly ranging cam member secured to

the partition, below the pivot and on the side of the smaller compartment.

2. A self latching milk box having two compartments separated by a pivoted partition, a cover for one of the compartments, hinged to one 5 wall of the box, the other compartment being open, cooperating latching means carried by the under side of the cover and the upper end of the partition, false bottom in the open compartment, spaced from the bottom of the box to form 10 a chamber for a spring, a helical tension spring in the chamber, the spring connecting the lower end of the partition with the corresponding end of the box, and a cam member attached to the pivoted partition, on the side facing the open 15 compartment, the cam surface being outwardly and downwardly inclined.

3. A self latching milk box having two compartments separated by a pivoted partition, a cover for one of the compartments, hinged to one 20 wall of the box, the other compartment being open, cooperating latching means carried by the under side of the cover and the upper end of the partition, the partition being pivoted at a point intermediate its ends, a spring forming a 25 resilient connection between the partition and the box for urging the upper end of the partition towards the covered compartment, and a cam member attached to the side of the partition, below the pivot point, the cam being in the open 30 compartment.

ARTHUR L. WILLETT.
